UNITED STATES PATENT OFFICE.

CLINTON M. BALL, OF TROY, AND SHELDON NORTON, OF WEST TROY, AS-SIGNORS OF ONE-THIRD TO ALEXANDER T. PORTER, OF WEST TROY, NEW YORK.

MAGNETIC ORE-SEPARATOR.

SPECIFICATION forming part of Letters Patent No. 404,333, dated May 28, 1889.

Application filed October 5, 1888. Serial No. 287,329. (No model.)

To all whom it may concern:

Be it known that we, CLINTON M. BALL, of Troy, in the county of Rensselaer, and SHELDON NORTON, of West Troy, in the county of 5 Albany, and State of New York, have invented certain new and useful Improvements in Ore-Separators; and we do hereby declare the following to be a full, clear, and exact description of the invention, such as will enable others 10 skilled in the art to which it appertains to make and use the same.

This invention relates to a novel apparatus for separating iron or its ore from the impurities with which such are generally found associated—for instance, phosphorus, sulphur in the form of pyrites, &c.

Briefly, the invention consists in an apparatus adapted to forcibly cause the tumbling or rolling of the particles of material through 20 a compound magnetic field of alternating polarity with or without the application of a current of air; and the invention further consists in the arrangement or construction of devices for the foregoing purpose, substantially as hereinafter fully described and claimed.

In the drawings which form part of this specification, Figure 1 is a vertical section of a complete apparatus constructed in accordance with the principles of our invention. 30 Fig. 1^a is a diagram illustrating the principle. Fig. 2 is a sectional elevation of a modified form of the apparatus. Fig. 2^a is a face view of the compound magnet, illustrated in three 35 different modes of construction. Fig. 3 is a longitudinal vertical section, and Fig. 4 is a transverse vertical section, of another modified form of the apparatus constructed in accordance with our invention.

40 Referring now to Fig. 1, we construct the hopper 1, having an adjustable gate, 2, adapted to spread the ore and gangue uniformly and to an even depth over an inclined apron, 3, which feeds into a vertical chute, 4, whose lower end is connected with the inlet of a rotary fan or blower, 5, which may be conveniently operated by the belt 6 and pulley 7 on

the counter-shaft 14. Situated on a framework of the structure are the two parallel shafts 8 9, and these carry the drums 10 and 11, over which is passed an endless belt, 12, drum 11 being driven positively by means of a belt from any suitable source of power. Both or either of the ends of the apparatus between the drums 10 and 11 and the face of 55 the inclined apron 3 may be open to the atmosphere, so that in the operation of the blower 5 currents of air are induced at these points and deflected downwardly into chute 4, as indicated by arrows in the figure. In 60 the space between the drums 10 and 11, I place a series of magnets, M M² M³ M⁴, &c., and these magnets may be either permanent or electro magnets, and they are so arranged as to have their free poles in close proximity to 65 the inner face of belt 12 next the inclined apron 3. The free poles are arranged in alternation as to polarity—that is, if the first pole is north, the second is south, the third north, and the fourth south, and so on throughout the series, which may be of any desired number. The shape of the poles may vary according to the will of the designer, and may be either elongated to the full width of the belt or to a less extent, or may be made up in 70 groups of circular magnets, all of which forms are indicated at Fig. 2^a.

The operation will be as follows: The ore and gangue passing down the apron 3 come within the attractive influence of the first pole 80 of the magnetic system, and all magnetic particles contained in the body of ore are immediately attracted and held against the moving belt 12, which on this side is moving downwardly, as indicated by the large arrow. All 85 the magnetic particles are attracted first to the first pole; but as the belt compels them to move forward toward the second pole their positions are reversed, and, leaving the second pole for the third pole, their positions are again 90 reversed, and so on past the series of magnets in succession, so that all the magnetic particles are not merely caused to adhere against the face of the belt, but as they pass along are

compelled to, as it were, tumble or turn end for end, and in this manner are very thoroughly agitated, and their friction upon one another and upon the belt, along with the mechanical agitation effected by the alternations of magnetic polarity, result in a most thorough cleansing of the magnetic particles from all dust or other impurities which would otherwise cling to them.

- 10 The peculiar action upon the magnetic particles is graphically illustrated in Fig. 1^a, where, for the purpose of clearness, a single particle is shown in its successive positions as it travels past the alternating poles of the 15 magnetic system, the particle being exaggerated in size in order to make the action clear. On inspection of this figure it will be observed that as the particle first approaches the magnetic system it becomes polarized by 20 induction and one end becomes attracted more strongly than the other, owing to this induced polarity, and as it passes such pole it stands on end, in accordance with the well-known phenomena of the lines of force in magnetic 25 substances. As it is carried forcibly past this pole its outer and free end tends toward the next pole of the magnetic field, and midway between the two the position of the particle is parallel with the belt, and when it reaches 30 the second magnetic pole it again stands on end, but this time on the opposite end from that on which it stood at the last stage, and so on throughout the entire series of poles of the compound magnetic field the magnetic 35 particle is drawn by the belt, and at the same time compelled by the magnetic attractions to tumble end over end, as it were, a sufficient number of times to absolutely cleanse it of all foreign substances and dust which might 40 be clinging to its exterior.

As the gangue approaches the chute 4 most of the unmagnetizable portions fall into the chute and are carried away by the current of air produced by the blower 5, and as a final 45 step toward perfectly cleansing the magnetic particles which are now past the chute and are ready to be delivered the induced current of air upwardly past the lower end of apron 3 has the effect of blowing away the 50 last traces of dust and all other impurities which may possibly be still clinging to the particles of magnetic ore, after which the belt carries them outside the magnetic field, and as they are no longer attracted they fall on the 55 lower end of apron 3, and are thus not merely separated from the gangue, but also perfectly cleaned.

In Fig. 2 the inclined apron is replaced by an endless belt, 15, traveling on the drums 60 16 and supported by the rollers 17, the hopper 1 and the gate 2 remaining substantially as in the previous construction. In this case the belt 12 and drums 10 and 11 are arranged horizontally, so that the under side of the 65 belt passes along in close proximity to belt

15, and the magnets M M², &c., are arranged, as before, between the two drums 10 and 11, with their free poles in close proximity to the back of the belt 12. The hopper 4 remains unchanged, as also the blower 5; but we have 70 placed the guide-plate 18, which forms the front wall of the closed receiving-chamber 22, in such position as to form a sort of flat nozzle at the upper rear edge of hopper 4, so as to more energetically direct the current of 75 air induced at that point by the action of the blower drawing air through the hopper 4 downwardly, and cause it to impinge upon the moving body of ore before the latter is carried out of the field of magnetic attraction; 80 and to avoid carrying back the smaller particles of magnetic ore by the air-current, and to prevent their accumulation at the discharge, the ore is received into the closed chamber 22, from which the flow of cleaned ore may 85 be regulated by the sliding gate 23.

In Figs. 3 and 4 the form is again slightly modified, and in this case the hopper 1 delivers into a narrow vertical chute, 19, in which is arranged to rotate a disk of diamagnetic 90 material, 20, carried by the shaft 21, and on the side opposite that in which chute 19 is located we place the group of magnets M M² M³ M⁴. The chute 4 is located at the lower end of the apparatus similarly to the previous forms, and the blower 5 is situated so as to act precisely the same as in the said previous forms. While somewhat changed in form and arrangement, all the foregoing modifications operate on precisely the same 95 principles and effect the same results.

While we have described a process herein, we do not lay claim to the same in this application, as we have incorporated claims to our process in a separate application, filed 105 September 26, 1888, Serial No. 286,398.

We claim as our invention—

1. An ore-separator comprising a group of magnets of alternating polarity, in combination with means for forcibly conveying the 110 ore past the said magnets successively without contact therewith.

2. An ore-separator comprising, in combination, a group of magnets of alternating polarity, a traveling screen adapted to move 115 across the poles of said magnets, and means for delivering the ore in proximity to the screen.

3. An ore-separator comprising, in combination, a group of magnets of alternating polarity, a traveling screen of diamagnetic material adapted to move across the poles of said magnets, and means for delivering the ore in proximity to the screen.

4. An ore-separator comprising, in combination, a group of magnets of alternating polarity, a traveling diamagnetic screen adapted to move across the poles of said magnets, means for delivering the ore to the outer side of said screen, and means for forcing a cur- 125 130

rent of air through the space traversed by the ore as it passes the magnet-poles.

5. An ore-separator comprising, in combination, a group of magnets of alternating polarity, a traveling diamagnetic screen adapted to move across the poles of said magnets, and an apron adapted to confine the ore within inductive range of said magnets and deliver it in close proximity to said screen.

In testimony whereof we affix our signatures to in presence of two witnesses.

CLINTON M. BALL.
SHELDON NORTON.
